UNITED STATES PATENT OFFICE

REINHOLD SCHWABAUER, OF BERLIN-STEGLITZ, GERMANY, ASSIGNOR OF TWO-THIRDS TO KARL STARKE, OF BERLIN, GERMANY, AND KARL PASCHKE, OF VIENNA, AUSTRIA

INTERCHANGEABLE PAD FOR BOOT HEELS

Application filed June 21, 1928, Serial No. 287,265, and in Germany January 30, 1928.

This invention relates to interchangeable pads for boot-heels which, by means of eyes or buttons, engage with indentations of the heel and are secured in this position by a 5 split-pin or similar fixation-means.

These known devices present the inconvenience that the eye or button is held in the indentation of the heel only at one side by a spring, bent in U-shape. In other devices 10 the heel-pad is fixed in the heel by means of an eye and split-pin. These fixations offer no security for a permanent adhering of the heel-pad on the heel, as, owing to the supporting on one side only, the button disengages from the indentations and the straight 15 split-pin or U-shaped spring gets disengaged from the eye in consequence of the vibrations at walking, so that the heel-pad drops off. The split-pin and spring might easily get 20 lost at the interchanging, as it has to be entirely removed.

These inconveniences are obviated, according to the invention, by guiding with friction the bent points of the split-pin in a sleeve 25 embedded in the heel. This sleeve prevents detaching of the split-pin and ensures that the split-pins, when the pad is being fixed on the heel, spreads further asunder after having been inserted through the eye so that 30 the points hook over the eye, when the split-pin is being pulled back or, if a button is used, the points grip over the button from both sides so that, even at vibrations, it cannot 35 get detached and holds permanently the heel-pad on the heel.

Two embodiments of the invention are illustrated, by way of example, in the accompanying drawing, in which:

Fig. 1 is a plan-view of the heel with pad 40 viewed from below.

Fig. 2 is a plan-view on the heel without the pad viewed from below.

Fig. 3 shows the pad in top-plan-view.

Fig. 4 shows the fixation-device in oper- 45 ative position.

Fig. 5 shows in top-plan-view seen from below a heel with a fixation-device of another form of construction.

Fig. 6 shows the heel-pad for the heel—Fig. 5 in top-plan-view seen from below.

Fig. 7 shows in top-plan-view the heel-pad—Fig. 6 fixed on the heel—Fig. 5 seen from below.

Fig. 8 is a longitudinal section of Fig. 7 on larger scale.

Fig. 9 is a longitudinal section of Fig. 4.

a is the heel-pad of rubber, *b* the heel of the boot, *c* the split-pin with outwardly bent ends, *c'* the guide-sleeve for the split-pin, *d* designates a slot in the heel designed to receive an eye *m*, fixed on the heel-pad *a* *f* are pins on the heel pad, *f'* are holes in the heel, designed to receive said pins *f*.

In Figs. 5 to 8 is *g* a button on the heel-pad and *h* a cavity in the heel designed to accommodate the button and the points of the split-pin *p*, embracing said button.

To fix a heel-pad *a* on a heel *b* the eye *e* or the button *g* is inserted into the slot *d* or cavity *h* respectively of the heel, whereupon the split-pin *c* is inserted so that the ends of its arms pass through the eye and project from the same, or grip around the button *g*, so that the point of the split-pin engages with the cavity *h*.

Owing to the outwardly bent ends of the split-pin *c* bearing against the guide-sleeve *c'*, when attempts are being made to pull out the split-pin, this pulling out is prevented. The points of the split-pin *c*, on emerging from the guide sleeve *c'* and the eye *e*, tend to spread outwardly owing to spring action and hook over the sides of the eye *e* so that accidental detaching of the pad from the heel is prevented.

I claim:

An interchangeable heel-pad for boot-heels comprising in combination with a heel having a cavity, a guide-sleeve extending from said cavity to the inner edge of the heel, 90

an eye on the upper surface of the heel-pad
designed to be inserted into said cavity, and a
split-pin the ends of the arms being bent
in outward directions said pin designed to be
5 inserted through said guide-sleeve in said heel
and through said eye so that the outwardly
bent points of the arms of the pin owing to
their tendency to spread hook over the sides
of said eye.

10 In testimony whereof I affix my signature.
REINHOLD SCHWABAUER.
